UNITED STATES PATENT OFFICE.

KALLMANN GLASS, OF NEW YORK, N. Y.

CABINET.

SPECIFICATION forming part of Letters Patent No. 621,067, dated March 14, 1899.

Application filed October 15, 1898. Serial No. 693,586. (No model.)

To all whom it may concern:

Be it known that I, KALLMANN GLASS, a citizen of the United States, and a resident of New York city, State of New York, have invented certain new and useful Improvements in Cabinets, of which the following is a specification.

This invention relates to a cabinet of novel construction and which combines in a peculiar manner a table or stand, a coal-bin, a wood-receptacle, a boot-blacking stand, and an ash-sifter, the latter two being removable from the body of the cabinet, so that they can be used separately.

15 In the accompanying drawings, Figure 1 is a front elevation of my improved cabinet; Fig. 2, a vertical section on line 2 2, Fig. 1; Fig. 3, a plan showing the drop-leaves *h* raised; Fig. 4, a section on line 4 4, Figs. 1 and 2; Fig. 5, a side view of the blacking-stand and ash-sifter combined, showing them withdrawn from the cabinet; and Fig. 6, a section on line 6 6, Fig. 5.

The letter *A* represents the body of the cabinet, having a raised bottom *a*, and a partition *a'* above the same to form an intervening kindling-wood receptacle *b*, accessible by a hinged front door *b'*. Above the receptacle *b* the cabinet *A* contains a coal-bin *c*, having an inclined false bottom *c'*, which guides the coal to the discharge-orifice, which is closed by a semicircular drop-lid *c''*. This drop-lid is provided with a semicircular peripheral flange *c'''*, which serves to confine the coal when the lid is open, and with a curved rear edge *c''''*, engaging a groove *a''* of partition *a'*. The drop-lid turns vertically on pivots placed centrally above the transverse groove *a''*, and the groove is struck from said lid-pivots as centers. Thus when the lid is opened this curved edge traverses the groove *a''*, and thus ejects any coal therefrom which would be apt to clog the lid.

Within the lower part of the cabinet *A* and below the raised bottom *a* is contained a sliding boot-blacking stand *d*, which can be bodily withdrawn from the cabinet, but which if in

place has its front *d'* flush with that of the cabinet. The stand *d* has a raised bottom *d''* to form an upper chamber, which contains 50 the foot-rest *d'''*, and is by a number of partitions *d''''* divided into compartments adapted to contain the blacking materials.

Below the raised bottom *d''* the front *d'* of stand *d* has a square opening that receives a 55 removable drawer *e*, sliding on rails *d''''* of stand *d*. This drawer is in turn provided with rails *e'*, upon which is supported a smaller inner drawer *f*, having a wire-gauze bottom *f'* and constituting an ash-sieve movable with- 60 in outer drawer *e*. The inner drawer may be manipulated by a handle *f''*, projecting through a perforation *e''* of outer drawer *e*, so that in this way the ashes may be screened without spreading any dust, the ashes drop- 65 ping into a pan *g*, placed upon bottom of drawer *e*.

To the top of the cabinet *A* there are hinged at both sides the drop-leaves *h*, adapted to be supported by laterally-swinging hinged brackets *h'*. The leaves *h*, as well as the top plate *a''* of cabinet *A*, are provided with a railing *i* to constitute a support or table for a gas-stove, wash-basin, or similar household article.

70 It will be seen that my cabinet is compact in structure and that it may be readily put to the uses for which it is designed.

75 What I claim is—

In a cabinet, the combination of partition 80 *a*, with door *b'*, inclined bottom *c'*, flanged drop-lid *c''*, sliding stand *d*, having raised bottom *d''*, foot-rest *d'''*, and rails *d''''*, outer drawer *e*, having rails *e'*, and sliding on rails *d''''*, inner drawer *f*, having wire-gauze bottom *f'*, 85 and handle *f''*, and movable within the outer drawer, substantially as specified.

Signed by me, at New York city, New York, this 5th day of October, 1898.

KALLMANN GLASS.
